ABRASIVE STICK HOLDER

Samuel Mark Hershey, Bala, Pa., assignor to
Albert P. De Sanno, Sr., Philadelphia, Pa.

Application July 28, 1932. Serial No. 625,297

2 Claims. (Cl. 51—206)

My invention relates to the mounting of abrasive wheels upon mandrels or arbors.

Abrasive sticks or abrasive wheels used for grinding straight, taper or spiral reamers, milling cutters, taps, dies, valves, pistons, steel brushings and hardened shafts, etc. ordinarily are circular in cross-section and are attached to a cylindrical arbor or mandrel by having a hole entirely through or partially thru its center. The arbor partially extending into the wheel is retained therein by cement or other analogous binding material. The cement gives no security because after a short use the fastening means disintegrate causing the separation of the arbor and abrasive.

As it is relatively costly to replace the abrasive stick and arbor, when separation occurs, it is desirable to merely have a permanent arbor and simply insert abrasive sticks in that arbor.

The present practice is to throw away, as obsolete, long abrasive sticks which are only worn at one end, as such sticks can not have their useful grinding surface extended.

It is, therefore, an object of my invention to provide an abrasive stick holder which may be used indefinitely and which will readily hold an abrasive stick or wheel.

Another object of my invention is to provide an abrasive stick holder such that if the end of the abrasive stick is worn, the same abrasive may be extended in the holder to utilize the grinding surface which has not been used.

Another object of my invention is to utilize a holder wherein the position of the grinding surface of the abrasive stick may be readily extended or shortened.

With the above objects in view, my invention consists of a holder for abrasive sticks having an arbor on which is mounted a plurality of flexible jaws to grasp the abrasive stick.

A further object of my invention is to construct a holder for a grinding wheel which wheel may be of various cross-sectional shapes such as round, elliptical, polygonal sections with irregular sides or star shaped sides.

Other objects of my invention are to provide an improved device of the character described, that is easy and economically produced, sturdy in construction and having a maximum efficiency.

With these and related objects in view, my invention consists in the following details of construction and combination of parts as will be fully understood from the following specification, when taken in conjunction with the accompanying drawing, in which:—

Figure 1 is an assembled side elevational view of a holder, embodying my invention, retaining an abrasive stick;

Figure 2 is a perspective disassembled view of my holder;

Figure 3 is a fragmentary perspective view of the jaws of a modified holder; and

Figure 4 is a fragmentary side elevational view of the modified jaws.

Referring more specifically to the drawing, I show in Fig. 1 a solid cylindrical abrasive stick 10 having one end therein gripped by a plurality of flexible metal jaws 12 of a cylindrical holder.

The open ends of the jaws 12 have a series of 70 tapered threads 14 cut on the outside to enable a threaded knurled coupling 16 to compress the jaws as the coupling is turned upon the threads of the jaws. The jaws 12 extend from a head or base 18 which has rigidly connected to it an 75 arbor or mandrel 20, the arbor or mandrel being adapted for easy insertion in a grinding chuck.

The holder shown in Fig. 1 is turned from a solid body, and the threads 14 are cut thereon. 80 When the predetermined outside diameters have been turned and the threads cut thereon, the threaded jaw end is interiorly drilled and reamed to render the holder hollow for receiving and supporting an abrasive stick therein. Slots 21 85 are then cut longitudinally to the medial axis from the open end of the holder to the base 18.

In Figs. 3 and 4 I show a modified cylindrical holder having a base from which extends a plurality of flexible jaws 22 for grasping an abrasive stick. A slot 24 for completing a bayonet joint extends transversely to the medial axis at the open cylindrical end of the abrasive holder. The slot 24 terminates at one end in a short slot which is substantially parallel to the radial axis of the 95 holder. A ring 26 has a radially extending stud 28 mounted on the interior surface of the ring. The stud 28 is of such width and length that it will readily slide within its complementary slot 24 and the terminating short slot, in order that 100 the jaws of the holder will be compressed or tightened about the abrasive stick when the ring 26 is inserted on the jaws. The ring with its stud 28 fitting in its complementary slot form a bayonet joint and enable a quick release of the abrasive 105 stick when the ring is removed as the jaws expand, and a rapid tightening of the holder jaws about the abrasive stick occurs when the ring is inserted on the holder jaws for locking the abrasive stick in position.

Altho this invention has been described in considerable detail, such description is intended as illustrative rather than limiting, as the invention may be variously embodied, and the scope of the invention is to be determined as claimed.

5 I claim:—

- 10 1. A holder for an abrasive stick comprising a hollow supporting member terminating in a tapered end portion, said member being longitudinally slitted whereby to render it compressible and said tapered end portion having a bayonet slot therein, and means fitted over said tapered end portion for compressing said tapered end to retain an abrasive stick therein, said means including an element adapted to cooperate with

said bayonet slot to retain said means fitted over said tapered end.

- 15 2. A holder for an abrasive stick comprising a hollow supporting member terminating in a tapered end portion, said member being longitudinally slitted whereby to render it compressible and said tapered end portion having a bayonet slot therein, and a ring member fitted over said tapered end portion for compressing said tapered end to retain an abrasive stick therein, said ring member including a stud adapted to interfit in and cooperate with said bayonet slot to retain said ring member fitted over said tapered end.
